UNITED STATES PATENT OFFICE.

LEE NORMAN DUNCAN, OF OKLAHOMA CITY, OKLAHOMA.

CARD CASE.

Application filed May 13, 1927. Serial No. 191,102.

This invention relates to a card case, out of which one card at a time can be taken without bending one away from another, fumbling among the cards, or in any way 5 touching or interfering with any of the others in the stack while taking the one.

The object of the invention is to provide for the automatic selection of one card at a time from a stack. Further objects of 10 the invention are to provide the simplest and most inexpensive method for the accomplishment of the desired results.

The invention, mechanically, may be expressed in any suitable embodiment, but 15 the one shown may perhaps be the preferred form or arrangement.

On the sheet of drawings accompanying and forming a part of the specification,

Figure 1 is a partial perspective of the 20 card case inverted, showing the cards in place and the position of the card selector (spring bar hooked at one end) in relation to the position of the cards;

Figure 2 shows a similar view, only in 25 reversed position;

Figure 3 is an enlarged view similar to Figure 2, designed to show more distinctly the position of a card on the hook of the selector;

30 And Figure 4 is a front elevation view of the card case. The case is to be of rigid, box-like construction, made of, and covered by, material to suit demand and manufacture, and is provided with a flap 6, and 35 the usual finger clearance 7 to facilitate the proper and uninterrupted removal of a card with the fingers.

Between the covering of the case and the

body thereof, a hook 8 overhangs the edge of the finger clearance 7 (see Figure 3) and 40 from this hook depends a spring bar 9 which terminates in a hook or beak 10 sufficiently lateral of the spring bar 9 to permit the deposit of only one card at a time (see the card 11 in Figure 3).

45 When the case is turned up-side-down (see Figure 1) all the cards rest on the bight of the flap 6. When the case is then turned right-side-up (see Figure 2) the cards fall to the opposite end except the one card 50 which is caught by the hook 10 and held in elevation above the contour of the finger clearance 7 ready to be easily removed with the fingers (see card 11 in Figure 4). So long as there is provided a mechanical card- 55 catcher that will catch one card at a time from a pack and hold that card in relative elevation to the others, it makes no difference as to the method of forming the card catcher.

60 What I claim as new and desire to secure by Letters Patent is:

A card case comprising a casing, a spring bar suitably secured within said casing, a 65 flange on the free end of the spring bar for engaging and holding in elevation one card from a pack when the card case is tilted from an inverted to a normal position, and a flap carried by said case to retain the cards when the case is in the tilted position. 70

Signed at Oklahoma City, in the county of Oklahoma and State of Oklahoma, this the 7th day of May, in the year of our Lord, nineteen hundred and twenty-seven.

LEE NORMAN DUNCAN.
